TWISTING OF STRANDS TO FORM A PLY CONSTRUCTION

Filed Sept. 7, 1944

UNITED STATES PATENT OFFICE

2,400,697

TWISTING OF STRANDS TO FORM PLY
CONSTRUCTIONS

Arthur P. Lewis, Fairhaven, Mass., assignor to
United States Rubber Company, New York,
N. Y., a corporation of New Jersey

Application September 7, 1944, Serial No. 552,994

5 Claims. (Cl. 57—58)

This invention relates to mechanism for twisting together a plurality of strands, and more particularly to a method of and means for equalizing the tension of such strands as they approach the point where they are twisted together.

In the Clarkson Patent No. 2,343,535 for Mechanism for twisting together a plurality of strands it is stated that the mechanism disclosed will not twist the strands together symmetrically to produce the desired ply construction unless the tension upon the different strands is equal or nearly equal, and the patent shows and describes one form of mechanism for automatically equalizing the tension of the strands as they approach the point at which they are twisted together.

While the mechanism disclosed in this Clarkson patent works very well, the present invention contemplates an improved construction over that of the Clarkson patent for equalizing the tension of the strands, the present construction being more simple than that of the Clarkson patent.

The construction of the present invention could be employed with various types of twisting mechanism for twisting strands together by advancing them in spaced relation to each other parallel to a central axis and at the same time revolving these strands about such axis to twist them together. The present invention however was developed primarily for use in connection with the type of twisting mechanism forming the subject matter of the above mentioned Clarkson patent, and is therefore shown and described as associated with that type of twisting mechanism.

In carrying out the present invention the yarns, cords or strands which are advanced in spaced relation to each other and to a central axis about which they are revolved to twist them together, are deflected inwardly towards the axis of rotation at a point along their path of travel so as to form a loop in each strand. These loops are floatingly connected so that one pulls against the other as the tension upon the strands tends to straighten out these loops. The result of this is that the amount each strand is deflected from its straight line position will be inversely proportional to its relative tension. That is if one strand is under high tension and the other strand is under a much lower tension, the high tension strand will have its loop practically straightened out so that it will pass relatively freely to the point at which the strands are twisted together, whereas the lower tension strand which at this instance will be deflected to form a deep loop will travel less freely to the point at which the

strands are twisted together. The effect of this is automatically to equalize the tension of the different strands within a substantial range.

One simple way of causing the strands to operate in this manner to equalize their tension is to cause one strand loop to physically engage and slide through the other strand loop, or if desired a floating guide such as a floating ring through which the strands slide may be employed to connect the loops so that one will pull against the other in such a manner that the depth of these loops will vary inversely with the relative tension of the different strands.

The extremely simple construction of the present invention for automatically equalizing the tension of such strands and method of equalizing their tension will be more fully understood from the following description when read in connection with the accompanying drawing wherein:

20 Fig. 1 is a schematic side elevation with parts in section of the twisting mechanism shown in the above-mentioned Clarkson patent, but equipped with the tension equalizing means of the present invention.

25 Fig. 2 on a larger scale is a longitudinal sectional view through the tension equalizing means shown near the right hand end of the twisting mechanism of Fig. 1; and

30 Fig. 3 is a view similar to Fig. 2 showing a modification of the invention.

The twisting mechanism shown in Fig. 1 of the drawing is designed to twist together yarns, threads or strands by forming a balloon in one strand and by revolving this balloon about the 35 let-off package of another strand to twist the strands together at a point intermediate their ends, without similarly rotating the let-off packages for the strands or the take-up package for the plied construction. The effect of this is to 40 ply the strands together without altering appreciably the manufacturing twist of the individual strands.

In Fig. 1 of the drawing there is shown what is termed the first let-off package 10 and a second let-off package 11. Both of these packages preferably have the conical construction shown so that the strand 12 may be withdrawn endwise from the package 10 and the strand 13 may be withdrawn endwise from the package 11 without the necessity of rotating these packages as the strands are unwound therefrom. The package 10 is mounted on a supporting cone 14 that is supported by the shaft 15 extending laterally from the frame or upright 16. The strand 12 upon being unwound from its package 10 passes through

a pigtail guide 17 disposed on the central axis through the package 10 but at some distance from the package, and this guide is supported by a bracket 18.

The strand 12 passes from the pigtail guide 17 through an opening 19 at one end of a flier arm 20 that is rigidly secured to the hollow twisting spindle 21, and extending opposite from the arm 20 is the counterbalancing arm 22. The twisting spindle 21 is rotatably supported by the machine frame or bracket 23 and is adapted to be driven by the whorl 24 and belt 25. The strand 12 after passing through the opening 19 travels along the arm 20 to the hollow spindle 21 and then through the hole 26 into this hollow shaft and lengthwise therein in a righthand direction.

The second let-off package 11 is shown as mounted upon a cone 27 which is supported by the hollow shaft 28, and this shaft is non-rotatably supported by the rotating spindle 21 through the ball bearings 29 consisting of the inner rings rigidly secured to a projecting end of the revolving spindle 21 and the outer rings tightly fitted within the casing 30 secured to the shaft 28. This ball bearing construction permits the hollow twisting spindle 21 to be rotated without rotating the spindle 28 which it supports, and in order to prevent the small amount of friction which may be imparted from the rotating spindle 21 to the spindle 28 from turning the latter, a weight such as 31 may be rigidly secured to the casing 30 to hang downwardly therefrom in a vertical direction and has at its outer end the projection 32 positioned to clear the full package 11.

In the construction shown the package 11 is supported so that its smaller end faces the smaller end of the first package 10, and the construction is preferably such that the strand which is unwound from the package 11 may be pulled endwise therefrom and then advanced axially through this package within the hollow supporting shaft 28. To accomplish this and at the same time prevent the unwinding strand from dragging unduly upon the smaller end of the conical package a fairly long tubular guide 33 is provided the inner end of which fits telescopically within the hollow tube 28. The outer end of this tubular guide has the enlarged beaded portion 34 over which the strand 13 may slide freely as it passes into the tube 33.

The mechanism just described constitute one form of mechanism for twisting together two or more strands, with which the construction of the present invention for automatically equalizing the tension of such strands may well be employed. The tension equalizing device of the present invention has therefore been shown as mounted upon the right hand end of the rotating hollow spindle 21, but it will be understood that the present tension device may be used upon other types of strand twisting devices than that shown in Fig. 1 of the drawing.

The hollow spindle 21 as will be apparent from Figs. 1, 2 and 3 of the drawing has provided at its discharge end a guide disc 35 in which is provided the strand guiding holes 36 disposed upon the opposite sides of and some distance from the central axis of the spindle 21 as shown.

To the right hand end of this hollow spindle 21 is secured the cup-like housing 37 having the closed end 38 in which are formed the spaced guide holes 39 adapted to be aligned with the holes 36. This housing as shown fits snugly over the outer end portions of the spindle 21 and is

preferably mounted for slidable longitudinal adjustment thereupon so as to vary the distance between the end walls 35 and 38 as will be apparent from Figs. 2 and 3. After the housing 37 has been adjusted upon the spindle 21 to the desired position it may be locked in this position by tightening the set screw 40.

The means shown in Figs. 1 and 2 of the drawing for automatically equalizing the tension of the strands 12 and 13 operate as follows. The strands 12 and 13 are drawn through the hollow spindle 21, and the strand 12 is threaded through the aligned guide openings 36 and 39 at one side of the spindle axis, whereas the strand 13 is threaded through the aligned guide openings 36 and 39 at the other side of the spindle axis. This may be done by using a wire with a hook on the end of it for drawing these strands 12 and 13 through the openings just mentioned. This will cause the strands 12 and 13 to lie in spaced parallel relation to each other within the casing 24. This casing is then preferably rotated through about 360° with respect to the hollow spindle 21 so as to twist each strand about the other as shown in full lines in Fig. 2. The set screw 40 is then tightened to lock the part in the position in which they are shown in Fig. 2. It will be seen from this view that each strand is now looped about the other strand within the receptacle 37, and the arrangement is such that one strand slides within the loop of the other as they advance toward the point where they are twisted together.

The point 41 at which the loop of one strand engages the loop of the other strand will be a floating point and will lie upon the central axis upon which the spindle 21 rotates only when the tension upon the two strands is substantially the same. If the strand 12 should be subjected to a tension considerably higher than that of the strand 13 the point 41 where the strand loops interengage will be shifted to some such point as 41' where the highly tensioned strand 12 assumes nearly a straight line position while it forms a deep loop in the strand 13 which is under less tension. The effect of this will be to cause the nearly straight strand 12 to pass more freely through the housing 37 than the deeply looped strand 13, with the result that the tension of these two strands will be about equal as they pass through the guide openings 39 to the point where they are twisted together. On the other hand if the strand 13 should be subjected to a greater tension than the strand 12 the point at which the loops are interengaged will be shifted to some such position as 41''.

While the construction shown in Fig. 2 of the drawing is extremely simple the sliding of the looped portion of one strand through the looped portion of the other strand may tend to chafe both strands. This difficulty may be overcome by employing the modified construction shown in Fig. 3 of the drawing in which a small guide ring 42 formed of metal or plastic material is employed through which the strands 12 and 13 will slide as shown. This ring 42 is floatingly supported by the looped portions of the strands 12 and 13 and will shift from the central axis of rotation towards the straight line position of one strand or the other as the relative tension of the two strands varies, it being apparent that the strand which is nearly straight will pass more freely through the ring 42 than the strand which is displaced to form a deep loop. This will tend

automatically to equalize the tension of the strands as they pass through the guide holes 38.

The amount of tension placed upon the strand 13 may be varied by wrapping this strand around the spindle 33 as at 43, and the tension the equalizing device of the present invention will exert upon the two strands 12 and 13 may be increased somewhat by adjusting the housing 37 from the full line position to the dotted line position in which it is shown in Figs. 2 and 3. This will cause the strands to form sharper loops so as to increase the tension which one exerts upon the other as they pass through the housing 37.

The strands 12 and 13 when plied together pass through the chuck 44 supported by the bracket 45, and these strands are pulled forward from their respective packages 10 and 11 and through the spindle 21 and housing 37 by the rolls 46 and 47, one of which is positively driven. The plied yarn is wound one or more times around these spaced rolls to prevent it from slipping.

It will be seen from the foregoing that the present invention provides an extremely simple construction for automatically equalizing the tension of strands as they approach the point where they are twisted together as described to form a ply construction.

Having thus described my invention, what I claim and desire to protect by Letters Patent is:

1. Twisting mechanism for twisting strands together to form a ply construction, comprising a revolving spindle having means for guiding strands lengthwise thereof in spaced relation to the spindle's axis to thereby twist the strands together upon said axis; and means for equalizing the tension of said strands as they approach the point where they are twisted together, comprising a floating guide for the strands adapted to deflect the strands inwardly towards said axis so as to form a loop in each strand whereby the guide is floatingly supported solely by such loops for movement towards the straight path of travel of the strand that is under the greatest tension.

2. Twisting mechanism for twisting two strands together to form a ply construction, comprising a revolving spindle having means for guiding the strands lengthwise thereof at opposite sides of the axis upon which the spindle rotates to thereby twist the strands together upon said axis; and means for equalizing the tension of said strands as they approach the point where they are

twisted together, comprising a member for deflecting each strand inwardly towards said axis so that each strand is held in a looped condition by the tension of the other strand and the depth of each loop will be inversely proportional to the relative tension of the two strands.

3. Twisting mechanism for twisting strands together to form a ply construction, comprising a revolving spindle having means for guiding the strands lengthwise thereof in spaced relation to the axis upon which the spindle rotates to thereby twist the strands together upon said axis; and means for equalizing the tension of said strands as they approach the point where they are twisted together, comprising a guide for deflecting the strands inwardly towards said axis and through which guide the strands pass so as to form a loop in each strand, said guide being floatingly supported by the strands whereby the depth of the loops will be inversely proportional to the relative tension of the strands.

4. The method of twisting together a plurality of strands to form a ply construction and of controlling the tension of the strands being twisted, which comprises advancing strands in spaced relation to each other and to a central axis and rotating them about said axis to twist them together; and equalizing the tension of said strands as they approach the point where they are twisted together by deflecting a portion of each strand inwardly toward said axis to form sliding loops that are floatingly connected so that one pulls against the other and the depth of each loop will be inversely proportional to its relative tension.

5. The method of twisting together a plurality of strands to form a ply construction and of controlling the tension of the strands being twisted, which comprises advancing strands in spaced relation to each other and to a central axis and rotating them about said axis to twist them together; and equalizing the tension of said strands as they approach the point where they are twisted together by deflecting a portion of each strand inwardly toward said axis to form sliding loops that are floatingly connected so that one pulls against the other and the amount each is deflected from its straight line position will be inversely proportional to the tension of each strand respectively.

ARTHUR P. LEWIS.
